METHOD OF AND MACHINE FOR MAKING PULP ROVINGS

Application filed June 6, 1931. Serial No. 542,649.

This invention relates to the manufacture of pulp rovings, for instance from wood pulp, being more especially concerned with an improved method of and machine for 5 making pulp rovings of uniformity, high strength, and other desirable characteristics at high speeds.

It has heretofore been proposed to produce rovings from short-fibered material, such as 10 wood pulp, by depositing the pulp as ribbons on a wire screen or cloth, and then furling the ribbons in damp condition by means of angularly-arranged belts into round form. Aside from the fact that the rigging necessary 15 for mounting and adjusting the belts is cumbersome and expensive, it is difficult to secure uniform rovings of good quality, particularly at high speeds, where there is danger of effecting incomplete or no furling of 20 the ribbons and/or of causing snarls or entanglements between the closely spaced pulp deposits. In addition to these defects, the belts are troublesome, because of buckling, twisting, and other distortions, particularly 25 when wide belts are used, such as are essential for large scale production.

We have found that the furling of the pulp ribbons may be accomplished on the very wire cloth on which they have been deposited 30 by the simple expedient of engaging their edge portions by a friction roll and rolling them out at an angle to the direction of travel of the wire, the roll being caused to rotate by the wire, if desired. The periphery of 35 the friction roll may be surfaced with any suitable material, but we prefer to use a roll of the same general type as the so-called dandy roll used in paper manufacture. This type of roll is covered with wire cloth of 40 relatively fine mesh, and serves to accomplish the desired function of furling or rolling the ribbons most admirably when they are in the proper state of dampness. Inasmuch as there is a tendency for fibers in the pulp ribbons to become entangled with the wire on 45 which they are deposited and thus to stick to the wire, we prefer to lift only their edge portions to be first engaged by the furling roll so as to ensure a furling or rolling action. 50 We do not, however, herein claim this fea-

ture as our invention, as this is fully disclosed and claimed in application Serial No. 542,648, filed June 6, 1931, by Frederick W. Vogel and William B. Meglitz.

We also prefer to dry the roll surface after 55 it has peripherally moved out of furling position so as to obviate any tendency of the rovings to stick to the furling roll, which, by contact with the damp pulp ribbons becomes moist. It is thus seen that not only 60 have we effected a simplification in the method and in the machine, but that, what is still more important, we can have high speed production, comparable to that at which high speed paper machines are run, while at 65 the same time securing uniform rovings of excellent quality. In this connection, it is to be observed that the speed of the wet end of the machine can, as will be appreciated by those skilled in the art, without difficulty 70 be made to run at as high as 500 or more feet per minute; and our invention makes possible the coordination of successful furling or roving of pulp ribbons with such speed 75 of manufacture.

It is most desirable that the furling roll have an effective operating surface of relatively large diameter. This feature was discovered only after experimentation and mathematical consideration of the forces 80 which affect what we may term the roving action. It has been established that the formula which governs the normal pressure between the drier felt and the drying cylinders of a paper machine is: 85

$$p = \frac{2T}{D},$$

where p is the normal pressure between the 90 felt and the cylinder, T is the tension in the felt, and D is the diameter of the cylinder. It is interesting to note that the pressure is independent of the arc of contact between the felt and cylinder. It appears that the 95 pressure on the pulp ribbons during roving follows the same formula, that is, it depends upon the diameter of the roving roll. Based on experience, we judged that the proper pressure would be, say, $\frac{3}{4}$ of a pound per 100

square inch, and the tension, say, 6 pounds per inch width of wire. Then,

$$D = \frac{2T}{p} = \frac{2 \times 6}{\frac{3}{4}} = 16"$$

Not at all obvious was the fact that the calculation did not require a consideration of the arc of contact between the roll and the wire, i. e., the roving or operative area. It can, however, be shown by analytical geometry that this arc of contact has no effect upon the pressure. In accordance with our invention, therefore, we use a roving roll of an effective diameter of at least about 16 inches, although when the roll is covered with a resilient or highly compressible material such as sponge rubber or its equivalent, the actual diameter of the roll may be less than about 16 inches, because of the flattening or distortion at the area of contact with the wire and the attendant increase in the effective diameter. Whether or not our hypotheses are correct, it is a fact that in actual practice the use of a roving roll having an effective diameter of at least about 16 inches makes for uniform and eminently satisfactory results; and, although the use of a roll of materially smaller effective diameter may be made to yield good rovings, the larger roll appears to be more fool-proof and permits of the simplest arrangement of guide rolls and the like.

With these and other features and objects in view, our invention will now be described in conjunction with the accompanying drawing, wherein

Figure 1 represents a side view, partly in section, of a machine embodying our invention.

Figure 2 is an elevation of the front end of the machine.

Figure 3 is a fragmentary sectional detail on the line 3—3 of Figure 1.

Figure 4 shows diagrammatically a section through a modified form of furling roll.

As shown in Figure 1, the wet end of the machine may include a suction roll indicated generally by the numeral 1 and a pulp vat indicated generally by the numeral 2. A wire cloth or screen 3, such as used on a Fourdrinier machine, passes tightly about the roll 1, which is provided with spaced, peripheral grooves (not shown), communicating with its interior so as to cause the deposition of pulp as spaced, continuous ribbons when an aqueous pulp suspension is run onto the roll from the vat 2. The vat is made up of a bottom 4 and side walls 5 whose front edges terminate in close proximity to the rolls so as to direct a flow of the pulp suspension onto the wire, the front edges 5a of the side walls being curved to conform to that portion of the roll periphery presented thereto. The roll proper is supported at its ends in suitable bearing members 6 and is rotated by suitable means (not shown), thereby serving to drive the

wire in the direction indicated by arrows. The vat receives a supply of pulp suspension of suitable consistency from a pipe 7 entering the vat bottom 8 at a point somewhat removed from the rear wall 9. The pulp suspension flows under a baffle plate or false bottom 10, provided with a downwardly projecting rear or dam portion 11 acting to confine the flow frontwardly. The pulp suspension flows onto the wire, and the water passes through the wire into the roll only over those areas or zones immediately in back of the spaced peripheral grooves, as a result of which ribbons of pulp are deposited on the wire. In order that a uniformly textured deposit of pulp be made, an excess of highly dilute pulp suspension is delivered into the vat, the excess taking the course indicated past the clearance or throat space 12 between the baffle and the roll, and thence over the baffle and dam to the rear of the vat. The excess pulp suspension may leave the vat through a pipe 13 returning it to the source of supply (not shown). The clearance 12 between the baffle and roll may be varied, as by constructing the baffle in two pieces, as shown, with the front piece 14 being longitudinally adjustable. The head of suspension in the vat may be controlled as by a vertically adjustable gate 15 arranged above the baffle 10 and immediately in front of the dam 11. The adjustment may be made as by a hand-wheel 16 outside of the vat and fixed to a vertical screw shaft 17 engaging a pair of spaced nut elements 18 on the gate. The pulp suspension employed may be of a consistency of only about 1/40% or even less, in which case large quantities of water are removed during the formation of the pulp ribbons. To this end, a suction chamber 19 occupying a sector somewhat greater than the peripheral portion of the roll in contact with the pulp suspension flow, may be arranged inside of the roll, so as to accelerate withdrawal of the water from the pulp and thus to promote the formation of pulp ribbons on the wire 3. The wire carrying the pulp ribbons out of the pulp suspension may then pass over a smaller second suction chamber 20 adjacent to the chamber 19. In depositing on the wire, while the pulp fibers assume a preponderantly longitudinal lay, particularly when the wire is traveling at such speeds as 500 feet per minute, or greater, a certain amount of cross-laying and random-laying of the fibers inevitably ensues, particularly on account of the turbulence and eddying of the pulp suspension as it flows through the clearance 12 and the currents of water cascading into the roll.

The wire carrying deposits of pulp ribbons proceeds horizontally from the roll 1 over the desired number of suction boxes 21 maintained under sufficient suction to dewater the ribbons to a water content of about 250% to 300%, more or less, based on the weight of

fiber. At this water content, the ribbons are amenable to ready furling or rolling into rovings or round bodies, but it is of course desired that the furling action be made positive and uniform. To this end, the wire passes over a pressure box 22, whereinto a gaseous medium under pressure, such as compressed air, is delivered by a pipe 23 from a pump or pressure chamber (not shown). The compressed air is emitted from the box, as best shown in Figure 3, through a series of apertures 24, arranged transversely of the top of the box and directly under the edge portions on only one side of the ribbons. Each air blast has the effect of progressively lifting the edge portion of a ribbon from the wire as the wire moves thereover without, however, weakening, rupturing, or dislodging the ribbons from their initial placement. In fact, the lifting is only temporary and merely detaches the edge portions of the ribbons from the wire so that the initiation of the subsequent furling or convoluting action thereupon is rendered easy and positive. The wire then passes over the guide roll 240, whence it takes a vertically downward course to a spaced guide roll 25. The vertical wire stretch $3a$ between the rolls 24 and 25 is where the furling can be most conveniently accomplished. For this purpose, a furling dandy roll 26, whose periphery is covered with wire cloth of about 45 or finer mesh, is shown in engagement with the confronting zone or stretch $3a$ over an appreciable arc of contact, the axis of the roll being inclined at an angle of, say, 80° , more or less, to the direction of travel of the wire and the ribbons supported thereon. The wire-cloth covering may be fixed as by welding to a series of spaced rings 27 constituting the rims of spiders 28 suitably anchored to the shaft 29 for the roll. The shaft illustrated is hollow and is provided with perforations 30 through its side walls to permit the passage therethrough of hot air or other heated gaseous medium which in flowing through the perforations and out through the wire-cloth covering dries the moist wire cloth before it makes contact with the damp ribbons on the traveling wire. Other heating means, such as electric units, may be arranged inside of the roll to dry the roll periphery and thereby to prevent clinging of the ribbons to the periphery. The roll shaft 29 may be journaled for rotation in a pair of brackets 31 extending from a transverse bar 32 toward the wire $3a$. As the pulp ribbons, indicated by the numeral 33 in Figure 2, enter the nip defined by the wire $3a$ and the roll 26, the relative angular movement between the wire and the roll causes a furling or lateral rolling out of the ribbons into round form, with the edge portions previously detached from the wire affording an easy furling start, particularly as the damp ribbons are pliable and of a quasi-dough-like consistency. The furling roll may be positively driven, although, as illustrated, the rotation of the roll is realized by frictional contact with the traveling wire. The furling or roving action compacts the pulp ribbons into uniform round bodies or strands 34, detached or readily detachable from the wire as they issue from the nip. The strands may be collected continuously as by a pneumatic system, such as described and claimed in application Serial No. 504,029, filed December 22, 1930, by Milton O. Schur. After collection, the rovings may be twisted, plied into yarns or strings, and dried. Provision is preferably made to vary the angle of inclination of the furling roll 26, for which purpose the bar 32 may have a centrally located pivot pin 35, normally fixed at its outer threaded end by a nut 36 to the cross-member 37 of pair of spaced standards 38. If desired, bolts 39 positioned near the ends of the bar 32 may project through arcuate slots 40 in the cross-member 37, so as to permit firm fixture of the roll to the cross-member by nuts 41. In adjusting the angularity of the roll, the three nuts are loosened, and, after the roll has been swiveled to the desired angularity, the nuts are tightened down against the member 37. In returning to the suction roll 1 from the roll 25, the wire takes an inclined upward course over a tightening roll 42, and then runs substantially horizontally over a guide roll 43 to the suction roll. The tightening means for the roll 42 may, for instance, comprise a hand-wheel 44 on a shaft 45 to which is fixed a pair of bevel gears 46, each of which meshes with a bevel gear 47 on one end of a horizontal screw shaft 48. Each screw shaft is in threaded engagement with a movable standard or support 49 for the roll, passing therethrough and being journaled and fixed at its other end to the machine frame 50. By turning the hand-wheel in the proper direction, the roll 42 may be made to move horizontally against the wire to take up such slack as may exist therein at any time. It is, of course, desirable to wash the wire free from residual fibers as by spraying water thereonto from a manifold 51 arranged transversely above the wire, near the roll 42 or at any other suitable location. So, too, the suction roll 1 preferably undergoes the action of water issuing from a manifold 52 arranged inside the roll near its periphery, so that residual fibers are cleared therefrom before it reaches the pulp-depositing station. Rather than using a hard-surfaced dandy roll or other friction roll of a diameter of at least about 16 inches for the furling operation, as indicated in Figure 4, a much smaller roll 53 may be used when the periphery 54 is made of sponge rubber or other compressible or resilient material which, in bearing against the wire $3a$, becomes so flattened or distorted at its region of contact $54a$ with the

wire as to constitute in effect the periphery of a roll of about 16 inches or greater diameter, as illustrated in dotted outline.

Employing the method and machine of the present invention, the ribbons of pulp are furled or roved directly on the forming wire, wherefore there is little liability to damage or destroy the uniformity of texture or formation previously realized at the wet end 10 of the machine. Again, by detaching the edge portions on only one side of the ribbons and by using a furling roll whose periphery is preferably made of wire cloth, there is little, if any, danger of intermingling the 15 ribbons during furling or roving, even when they are as closely spaced as $\frac{1}{2}$ to $\frac{3}{4}$ inches apart; and the rovings separate from the wire quite readily. The furling action is positive and uniform, by which we mean that 20 there is no tendency to miss catching or engaging the detached edge portions and convoluting them into round bodies or strands entirely free from raggedness or lines of cleavage in its structure. The pulp ribbons 25 are compacted during roving, but with no danger of breaking them. Some water is removed during roving, the pulp ribbons having a water content of, say, about 300%, based on fiber, before roving.

30 By arranging the axis of the furling and compacting roll at an angle of 80° , more or less, to the longitudinal path of movement of the wire but in parallelism with the surface of the wire, the movement of the periphery of the roll is mainly in the direction of the movement of the wire, but has a lateral component sufficient to effect the desired furling or rolling out of the ribbons without, however, causing their intermingling or 35 snarling. The arc of engagement between the roll and the wire should be appreciable, as shown, and may, of course, be varied by adjusting the tension in the wire and consequently the amount of give or inward bulging 40 of the wire at its roll-engaging or operative portion, in the case of the resilient roll shown in Fig. 4. In the case of the non-resilient roll 28, shown in Fig. 1, the increased arc of contact is obtained by loosening the carrying wire and by pushing the roll 28 inwardly against the wire. The furling of the ribbons on the forming wire can be accomplished at high speeds and while they are quite damp,—conditions under which it would be 45 exceedingly difficult to operate without breakage and other troubles if the ribbons were stripped from the wire and transported through an atmospheric gap to furling mechanism such as belts. Despite the fact that 50 the edge portions on one side of the ribbons are detached from the forming wire to facilitate initiation of their furling and compacting, nevertheless they are maintained against misplacement by those fibers on their 55 opposite edge portions still in entanglement

with the wire as a result of previous forming and sucking the pulp onto the wire.

The combination of instrumentalities described is subject to modification, particularly as regards the means for forming or 70 depositing the pulp ribbons from aqueous suspension on the wire. The particular means shown and described, including the assembly of the forming wire, suction roll, and vat, has been found to give excellent results in actual practice, but, inasmuch as it 75 is the invention of Roy E. Brawn and has been described and claimed in application Serial No. 542,610, filed June 6, 1931, we 80 make no claim herein thereto, except in so far as it constitutes broadly an element of our invention. Broadly speaking, we employ a circuitously-traveling wire cloth made up 85 essentially of two horizontal stretches and a vertical stretch at one end at which furling of the pulp ribbons is accomplished after the ribbons have been suitably formed from aqueous suspension at the other end and have undergone partial dewatering on their way to the vertical stretch. While it is preferable to lift only the edge portions of the 90 pulp ribbons from the forming wire before roving, the entire ribbons may be detached as with an air shower. When the ribbon is furled on the forming wire, it is important to detach at least an edge in order 95 to permit free roving. This latter combination of detaching the ribbons as a whole from the wire and then roving the detached ribbons on the wire by means of a furling roll is 100 the practice which we inaugurated before the advent of the improved method of lifting only one edge. As already indicated, although the roving roll may be independently 105 driven, we prefer to have it rotated through contact with the wire, for the reason that, unless the roll is driven at exactly the right speed, the rovings are damaged. When a 110 properly balanced roll is mounted in good bearings, there is no difficulty in driving it by means of the wire in spite of the fact that the axis of the roving roll is not at right angles to the direction of travel of the wire. This is an important feature, for it was only 115 through actual trial that we established the fact that it was possible to drive the inclined roll without getting into trouble. On the other hand, the driving of the roll independently requires a finely adjustable variable speed drive; and a roll independently driven 120 is always a potential source of considerable trouble.

What we claim is:

1. The combination with a traveling carrier for ribbons of damp, interfelted fibrous material, of a roll frictionally engaging said carrier to define a nip into which said ribbons may pass, the axis of said roll being arranged at an angle of inclination to the direction of travel of said carrier. 130

2. The combination with a foraminous traveling carrier and means for depositing ribbons of pulp on said carrier, of a roll frictionally engaging said carrier to define a 5 nip into which said ribbons may pass, the axis of said roll being arranged at an angle of inclination to the direction of travel of said carrier.
3. The combination with a traveling wire cloth and means for depositing ribbons of 10 pulp on said cloth, of a wire-cloth-peripheried roll frictionally engaging said traveling cloth and ribbons and arranged at an angle of inclination to the direction of travel of 15 said carrier.
4. The combination with a traveling carrier for ribbons of damp, interfelted fibrous material, of a roll frictionally engaging said carrier to define a nip into which said ribbons may pass, the axis of said roll being arranged at an angle of inclination to the direction of travel of said carrier and said roll being mounted so as to be rotated by said carrier.
5. The combination with a traveling wire cloth for ribbons of damp, interfelted fibrous material, of a wire-cloth-peripheried roll frictionally engaging said carrier and ribbons and arranged at an angle of inclination 20 to the direction of travel of said carrier, said roll being mounted so as to be rotated by said wire cloth.
6. The combination with a traveling carrier for ribbons of damp, interfelted fibrous material, of a roll frictionally engaging said carrier and ribbons and arranged at an angle of inclination 25 to the direction of travel of said carrier, said roll being surfaced with a resilient material and flattened out at its carrier-engaging portion to constitute a roll having an effective diameter larger than when unflattened.
7. The combination with a traveling wire cloth, means for depositing from aqueous suspension 30 ribbons of wet pulp on said cloth, and means for partially dewatering said ribbons on said cloth, of a wire-cloth-peripheried roll frictionally engaging said cloth and ribbons and arranged at an angle of inclination 35 to the direction of travel of said wire, and means for drying the periphery of said roll after it moves out of engagement with said damp ribbons.
8. The combination with a traveling wire cloth and means for depositing from aqueous suspension 40 ribbons of wet pulp on said cloth, of a wire-cloth-peripheried roll frictionally engaging said cloth and ribbons and arranged at an angle of inclination to the direction 45 of travel of said wire, and means for adjusting the angularity of said roll.
9. The combination with a circuitously traveling wire cloth made up essentially of two horizontal stretches and a vertical stretch 50 at one end, means for depositing ribbons of pulp from aqueous suspension on said cloth at said other end, and means for partially dewatering the ribbons before they reach the vertical stretch, of a wire-cloth-peripheried roll frictionally engaging said vertical 55 stretch of cloth and ribbons and arranged at an angle of inclination to the direction of travel of said wire.
10. The combination with a traveling carrier for ribbons, of damp, interfelted fibrous material, of a roll having a diameter of at least about 16 inches, frictionally engaging said carrier to define a nip into which said ribbons may pass, the axis of said roll being arranged at an angle of inclination to the direction of travel of said carrier.
11. The combination with a traveling wire cloth and means for depositing ribbons of pulp on said cloth, of a wire-cloth-peripheried roll having a diameter of at least about 16 inches engaging said traveling cloth and ribbons and arranged at an angle of inclination 60 to the direction of travel of said carrier.
12. A method which comprises progressively depositing from aqueous suspension 65 pulp fibers as ribbons on a traveling foraminous carrier, and, while on the carrier, leading said ribbons into a nip by way of a tapered ingress defined by said carrier and a member moving continuously into contact with said carrier in a curved path and at an angle to the direction of travel of said carrier, thereby frictionally engaging the edge portions of said ribbons and rolling them out 70 into round form.
13. A method which comprises progressively depositing from aqueous suspension 75 pulp fibers as ribbons on a traveling wire cloth, and, while on the cloth, leading said ribbons into a nip by way of a tapered ingress defined by said wire cloth and another wire cloth moving continuously into contact with said first-mentioned wire cloth in a curved path and at an angle to the direction of travel of said first-mentioned wire cloth, thereby frictionally engaging the edge portions of said ribbons and rolling them out 80 into round form.
14. A method which comprises progressively depositing from aqueous suspension 85 pulp fibers as ribbons on a traveling foraminous carrier, and, while in the carrier, leading said ribbons into a nip defined by said carrier and a member which moves continuously into contact with said carrier in a curved path at an angle to the direction of travel of said carrier and whose arc of curvature in contact with said carrier corresponds to that of a roll having a diameter of at least 90 about 16 inches, thereby frictionally engaging the edge portions of said ribbons and rolling them out into round form.
15. A method which comprises depositing 95 from aqueous suspension pulp fibers as ribbons on a traveling wire cloth and, while on 100
- 110
- 115
